J. H. BELL,
TELEGRAPH SYSTEM,
APPLICATION FILED JAN. 3, 1918.

1,379,243.

Patented May 24, 1921.

UNITED STATES PATENT OFFICE.

JOHN H. BELL, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

TELEGRAPH SYSTEM.

1,379,243.

Specification of Letters Patent.

Patented May 24, 1921.

Application filed January 3, 1918. Serial No. 210,148.

To all whom it may concern:

Be it known that I, JOHN H. BELL, a citizen of the United States, residing at South Orange, in the county of Essex, State of New Jersey, have invented certain new and useful Improvements in Telegraph Systems, of which the following is a full, clear, concise, and exact description.

This invention relates to telegraphic systems and more particularly to systems of submarine telegraphy.

The principal object of this invention is to provide an improved organization of apparatus for overcoming the phenomenon known as "wandering zero" experienced in line conductors having high electrostatic capacity.

It is well known that due to the high condenser effect and the resulting low time constant of submarine telegraph conductors, a preponderance of current of one polarity will have the effect of counteracting or dominating a current of inverse polarity to the extent that a so-called choking of the conductor is likely to delay or otherwise interfere with signaling impulses. It is therefore considered desirable in signaling over lines of this character to employ, if possible, means for establishing true reversals of current polarity in order that uniformity in the charging and discharging of the cable may be had.

To the above end the present invention contemplates the use of a plurality of electroresponsive devices to coöperate with a transmitting system in establishing operations whereby a cable or line conductor will be connected to the earth during such impulse intervals as would otherwise require that a recurrence or a successive repetition of current impulses of like polarity should take place.

This system is illustrated diagrammatically in the accompanying drawing, in which only so much of a telegraphic transmitting system is shown as will be necessary to a clear understanding of the invention.

In the drawing, Figure 1, is shown a transmitting system suitable for practising the features of this invention, and in Fig. 2 is shown in a theoretical form the relation of current impulses which form permutations of polarities suitable for the transmission of signals.

In the embodiment chosen for illustrating this invention, the transmission arrangement has for convenience been based on the use of the well known five-unit code selecting system of Baudot, and before entering upon a more detailed description of the system a brief allusion will be made to the general features of the equipment.

A plurality of transmitter contacts collectively indicated by a reference character A, may be understood as arranged to be under the control of a perforated transmitting tape, as well understood in the telegraph art. A group of relays B under the control of the contacts A establish changes of current polarity by way of contacts controlled by a group of relays C with the segments of a multiplex distributor D at which a line or cable conductor 99 is terminated. The relays C serve to substitute an earth connection for intervals corresponding with successive repetition of impulses of like polarity which may have been selected by the relays B, for energizing segments of the distributor D, through which predeterminedly prepared combinations of current or earth connections become effective with the line 99.

In more specifically describing this system, it will first be pointed out that for convenience of description a dividing line 69 separates a transmitter equipment suitable for operating a single channel of the multiplex equipment which lies at the left-hand side of this line, from a transmitting equipment for a second channel of the multiplex which is shown at the right-hand side of the line 69. Although the distributor D has been shown in developed form, it will be understood that it should preferably be of a rotary type, and if the distributor is of quadruplex capacity the equipment shown at the left-hand side of the line 69 would correspond with one quadrant or arm, while the equipment shown at the right-hand side of the dividing line would correspond with another quadrant or arm of the distributor.

By inspection of the drawing it will be noted that a negatively poled source of grounded current 60 is connected over a common or bus conductor 59 with the left-hand or normal contact stop of each one of the transmitter contacts of the first channel and with the right-hand or forward stop of each transmitter contact of the second channel,

while a positively poled source of grounded current 50 is connected by way of a bus conductor 49 with each one of the forward or right-hand contact stops of the transmitter 5 contacts in the first channel and with the left-hand or normal contact stop of each transmitter contact in the second channel. It will also be noted that each relay of the group B is under the control of a corresponding one of the transmitter contacts A. A bus conductor 70 connected from one winding terminal of each of the five relays B of the first channel extends to the negative bus conductor 59, while a bus conductor 80 10 extends from one winding terminal of each of the five relays B of the second channel to the positive bus conductor 49. Therefore, so long as a transmitter lever in either channel is on its normal contact stop no current 15 will flow through the associated one of the relays B. When a transmitter lever is moved from its normal to its oppositely energized contact stop, however, a circuit will be established for the associated relay B 20 through which current from the battery 50 will act accumulatively with current from the battery 60, thereby operating the relay. 25

The control circuits of the compound-wound relays C may be seen to be arranged 30 in such a manner that each relay is connected to the respectively adjacent left-hand and right-hand positioned ones of the transmitter levers A. The connective relation of the two windings on each of these relays is 35 such that when currents of like polarity are applied to the non-grounded terminal of each winding the relay will be operated. It will therefore be clear that so long as two adjacent transmitter levers are both on 40 either their negative or their positive contact stops the associated relay C will be operated, and conversely, during such time as the two adjacent transmitter levers may be positioned, one on its negative stop, while the 45 other lever is on its positive contact stop, the associated one of the relays C which falls intermediate these transmitter levers will be deenergized. It therefore follows that during the time all of the transmitter levers A 50 are in their normal positions, all of the relays C, except the two relays 5 and 55, will be operated by current either from the source 50 or the source 60 which complete circuit through the transmitter contacts and 55 both windings of each relay to the earth connections. In order that the position of the equipment will be consistent with the circuits normally established, the relays C are shown in their respectively normal positions 60 as energized or non-energized.

For convenience in further describing this system, let it now be assumed that in response to one control tape for the first channel and another control tape for the second 65 channel, the transmitter contacts A will be

positioned to prepare permutations of current impulses which will correspond with the ten impulse intervals shown in Fig. 2 of the drawing. For this combination the transmitter levers at 1, 31, 41, 61 and 91 will 70 remain on their normal contact stops, while the levers at 11, 21, 51, 71 and 81 will be moved to engage their respective forward contact stops. The result of these circuit changes is the operation of the relays 12, 22, 75 52, 72 and 82 of the group B, and the releasing of the relays 15, 35, 65, 75 and 95 of the group C. The relays 2, 32, 42, 62 and 92 of the group B continue inert, while the relays 25, 45, 55 and 85 of the group C 80 continue operated. The relay 5 continues in its normal inert position. To specifically point out the differential circuits whereby the six relays of the group C are deenergized during the present combination, negative current 85 from the transmitter contacts 1 through the right-hand winding of the relay 5 to earth is opposed by positive current from the transmitter contacts 91 established over a conductor 79 through the left-hand winding 90 of the relay 5 to earth, thereby releasing this relay. In a similar manner, oppositely poled currents from the transmitter contacts 1 and 11 deenergize the relay 15, the contacts 21 and 31 effect releasing of the relay 95 35, contacts 51 and 61 cause relay 65 to release, contacts 61 and 71 cause the relay 75 to release and the contacts 81 and 91 cause the relay 95 to be released. It may be mentioned that negative current from each of the 100 transmitter contacts 41 and 51 causes the relay 55, normally inert, to be operated.

Since automatic transmitting mechanism (not shown) retains the circuits just traced until a trailer or contactor brush 40 has traversed its path from left to right on the distributor D, let it now be assumed that this brush has arrived over the first segment 8. A circuit may accordingly be traced from a negatively poled and grounded line 110 battery 20 by way of a bus conductor 19, the contacts 3 of the relay 2, the contacts 6 of the relay 5 to the segment 8, from which point the circuit continues through the brush 40 to a ring section 39 and thence to 115 the line conductor 99. For the next impulse a circuit may be traced from a positively poled and grounded line battery 30 by way of a bus conductor 29, the contacts 14 of the relay 12, the contacts 16 of the 120 relay 15 to the segment 18, and on the brush 40 arriving over this segment such positive impulse will be transmitted to the line 99. On arriving at the segment 28 the brush connects the cable through the contacts 27 125 of the relay 25 with a bus conductor 89 which is connected through a resistance unit 90 to earth. From the negative current bus 19 a connection extends over the contacts 33 of the relay 32, and the contacts 36 of the re- 130

lay 35 to the segment 38, from which the brush 40 next establishes this prepared impulse of negative current with the line 99. The segment 48 is connected with the ground 5 bus 89 through the contacts 47 of the relay 45, and the segment 58 is connected through the contacts 57 of the relay 55 with the ground bus 89; therefore in passing over these segments the brush 40 causes the cable 10 99 to be grounded. Current from the positively poled bus 29 completes circuit over the contacts 63 of the relay 62, the contacts 66 of the relay 65, and at a proper moment from the segment 68 by way of the brush 15 40 to the line 99. At the segment 78 the brush connects the line 99 through the contacts 76 of the relay 75 and the contacts 74 of the relay 72 with the negative bus 19. When over the segment 88 the brush 20 40 causes the line to be grounded through the contacts 87 of the relay 85, and on finally arriving over the last segment 98 the brush 40 connects the line through the contacts 96 of the relay 95 and the contacts 93 of the 25 relay 92 with the positive current bus 29.

From the foregoing description it will be clear that a succession of impulses prepared by the transmitted equipment in accordance with the uppermost current line in Fig. 2 30 would require five successive impulses in the order of a negative, positive, positive, negative and negative impulse for the first telegraphic channel, while five successive impulses in the order of a negative, positive, 35 negative, negative and positive impulse would be required for the second channel of the multiplexed line. Referring to the lowermost current line in Fig. 2, the blank intervals in this line correspond with the 40 intervals during which the cable or line 99 was grounded in substitution of the prepared impulses of current as indicated at the corresponding impulse spaces in the upper current line. For the first channel the 45 successive changes taking place with the line 99 were in the order of a negative impulse, a positive impulse, ground interval, a negative impulse and a ground interval. For the second channel the transmission progressed 50 in the order of a ground interval, a positive impulse, a negative impulse, a ground interval and a positive impulse.

It will be understood that receiving equipment at the distant end of the cable 99 will 55 be present to suitably translate the impulses and changes of electrical condition of the line into respective message records.

For convenience in the foregoing description it was assumed that the control tape 60 of the first and second channel respectively prepared their combination of impulses at the same time; it will be understood however that this would not necessarily be the case as it would only require that the 65 circuits of the second channel be prepared in

advance of the arrival of the brush 40 over the last segment 48 in the distributor section of the first channel. It will also be further understood that the tape control mechanism (not shown, but well understood 70 in the art) would not act to clear out a set up of the circuits of the first channel until the brush 40 had passed from the first segment 58 of the second channel. This relation of the channels would, of course, apply between each channel or quadrant of a quadruplex distributor or the sextants of a sextuplex distributor, etc. It will, of course, be obvious that instead of two or more channels, the distributor may be arranged to operate only a single channel, in which case the brush 40, after leaving a last segment as the segment 48, would enter upon a first segment or a segment interconnected to correspond with the segment 8. 75

Since the form and circuit arrangement of each of the relays in the group B are typical one relay with another, and as this is also true of the relays in the group C, one with another, uniform progressions of reference 90 numerals have been employed in designating like parts of the various equipments which correspond with the several segments or impulse intervals of the distributor. It will, accordingly, be convenient to trace 95 any one of the various permutations or combinations of impulses which this system is capable of preparing and transmitting, therefore further description of the system will not be necessary.

What is claimed is:

1. In a system of telegraphy in which signaling is effected through permutations of impulses having different polarities, a line circuit, a plurality of transmitting contacts, a plurality of relays controlled by said contacts, a distributor, means jointly controlled by said plurality of contacts, said relays and said distributor for establishing changes of current polarity with said line, and a second 105 plurality of relays controlled by said transmitting contacts to render the distributor effective to ground said line in substitution of an immediately succeeding repetition in said line circuit of an impulse of one polarity. 110

2. In a telegraph system, a line conductor, sources of current having opposite polarities, transmitting contacts, a distributor, relays controlled by said contacts for establishing permutations of current polarities with said distributor, means operated by said distributor for establishing said permutations of polarities with said line circuit, a plurality of compound wound relays, means 115 controlled by successively adjacent ones of said transmitter contacts for controlling the operation of respectively associated ones of said last mentioned relays, and means controlled by said compound wound relays to 120 125 130

render said distributor effective to ground said line in substitution of successive repetitions of the transmission thereto of current of the same polarity.

5. A telegraph system comprising a line, sources of current of opposite polarity, transmitting means, means controlled by said transmitting means for establishing permutations of current impulses with said 10 line, and means rendered effective upon the operation of said means by successive current impulses of the same polarity for grounding said line in substitution of successive repetition of current impulses of the 15 same polarity.
4. A telegraph system comprising a line, a plurality of sources of current of opposite polarity, a tape transmitter, a plurality of relays energized in accordance with the actuation of said transmitter, a distributor for applying to said line current impulses as established by the operation of said relays, and a second group of relays controlled by said transmitter for effectively grounding 20 said line in substitution of successive repetition of current impulses of the same polarity.
5. In a telegraph system, in combination with a distributor having a plurality of 25 transmitting segments, a pole-changer relay for each of said segments, a selecting switch individual to each of said relays for controlling the operation thereof, and a set of differential relays, each of which is under

the joint control of two adjacent selecting 35 switches and operating when both said switches are operated to disconnect a corresponding segment of said distributor from its associated pole changer and to connect it to ground.

6. In a telegraph system, in combination with a distributor having a plurality of segments, a pole changer relay for each of said segments, a selecting switch individual to each of said relays and having the contacts 45 thereof arranged to normally render said relays inert, and a set of differential relays operated in accordance with the actuation of said selecting switches for controlling the connection of the associate pole changer with 50 a corresponding segment of said distributor.

7. In a telegraph system, in combination with a distributor having a plurality of segments, a pole changer relay for each of said segments, a selecting switch individual to 55 each of said relays and having the contacts thereof arranged to normally render said relays inert, and a set of differential relays operated in accordance with the actuation of two adjacent selecting switches for disconnecting a corresponding segment of said distributor from its associate pole changer and to connect it to ground.

In witness whereof, I hereunto subscribe my name this 27th day of December, A. 65 D., 1917.

JOHN H. BELL.
